Primary Examiner — Mitchell I. Siegel

(74) Attorney, Agent, or Firm — AdamsIP, LLC; Earl
Walter Reed, III; James Hunter Adams(57) **CLAIM**

The ornamental design for a golf putter, as shown and described.

DESCRIPTION

FIG. 1 is a top front perspective view of a golf putter showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross-section view of the golf putter taken along line 8-8 in FIG. 2.

The dashed broken lines in the figures show portions of the golf putter subject matter that form no part of the claimed design.
